UNITED STATES PATENT OFFICE.

SAMUEL N. BARKER, OF KALAMAZOO, MICHIGAN.

DESIGN FOR A BACK FOR PLAYING-CARDS.

SPECIFICATION forming part of Design No. 36,963, dated June 14, 1904.

Application filed April 7, 1904. Serial No. 202,096. Term of patent 14 years.

To all whom it may concern:

Be it known that I, SAMUEL N. BARKER, a citizen of the United States, residing at the city of Kalamazoo, in the county of Kalamazoo, State of Michigan, have invented a new, original, and ornamental Design for a Back for Playing-Cards.

My new, original, and ornamental design for a back for playing-cards is clearly illustrated in the accompanying drawing, which is a plan view thereof.

What I claim as new, and desire to secure by Letters Patent, is—

The ornamental design for a back for playing-cards, substantially as shown.

SAMUEL N. BARKER.
